(57) **CLAIM**

The ornamental design for a lateral flow device, as shown and described.

DESCRIPTION

FIG. 1 is a perspective view of a lateral flow device;
FIG. 2 is a front view of the lateral flow device shown in FIG.

1;
FIG. 3 is a top view of the lateral flow device shown in FIG.
1;

FIG. 4 is a side view of the lateral flow device shown in FIG.
1; and,
FIG. 5 is a bottom view of the lateral flow device shown in
FIG. 1.

The broken line showing of structural features is included for
the purpose of illustrating non-claimed subject matter and
forms no part of the claimed design.
